UNITED STATES PATENT OFFICE.

MAURICE HOFHEIMER, OF BALTIMORE, MARYLAND.

CAN-FILLING MACHINE.

1,367,259.

Specification of Letters Patent.

Patented Feb. 1, 1921.

Application filed May 2, 1918. Serial No. 232,054.

To all whom it may concern:

Be it known that I, MAURICE HOFHEIMER, a citizen of the United States of America, and resident of Baltimore, in the State of Maryland, have invented certain new and useful Improvements in Can-Filling Machines, of which the following is a specification.

This invention relates to can filling machines and particularly to machines which measure or deliver a predetermined quantity of material to the cans being filled and the said invention is designed primarily for use in transferring paint from a large container to small cans.

An object of this invention is to produce a can filling machine which is readily adjustable for the purpose of varying or changing the quantity of material, such as paint, which is delivered to cans, thus making it possible to expeditiously adjust the apparatus to deliver paint for filling cans of different sizes from a container having a batch of paint of a certain color or shade.

A further object of this invention is to provide a measuring device having novel means whereby the mechanism is adjustable to increase or diminish the amount of material to be delivered, the same being proportional to the cans or receptacles to be filled, and the said mechanism being effective to increase or restrict the movement or throw of a piston designed to draw the fluid from a container and then deliver it to the cans, thus making the operation positive and accurate, so that there will be no appreciable variation of the amounts delivered by successive strokes or operations of the liquid moving elements.

A still further object of this invention is to provide novel means whereby the apparatus can be readily cleaned so that paints of different colors may be operated upon successively without the paint of one color being affected by a paint which had been previously run through the apparatus, so that it is possible to dispose of the whole or part of the paint of a certain shade and

without undue trouble put the apparatus in condition for running paint of another shade through it, the same being accomplished without, in any way, impairing the apparatus and without employment of costly means to accomplish the end.

A still further object of this invention is to provide discharge tubes or nozzles of different sizes to be used in connection with cans of different sizes so that the flow of fluid or paint can be directed to small or large openings when the receptacle is to be filled, and the invention also contemplates the provision of novel means for preventing the sealing of the nozzle by capillary attraction and insuring the flow of paint from the said nozzle by gravity after the forcing mechanism has come to rest. The invention furthermore includes the provision of novel means for arresting the drippings and discharging accumulated drippings into a receptacle where they can be collected for disposal.

A still further object of the invention is to provide a discharge pipe having a baffle wall extending upwardly from its bottom, so that only that fluid or paint which has passed the baffle will gravitate from the discharge nozzle and by this means, undue dripping is obviated.

A still further object of this invention is to provide novel means for regulating the speed of operation of the apparatus and providing a motor with interposed power transmitting mechanism having ready means of adjustment for increasing or diminishing the revolutions of the driving means as compared with the revolutions of the motor shaft and the interposed mechanism.

A still further object of this invention is to provide novel means for operating the liquid transmitting or moving means and the drip collector synchronously and furthermore to provide novel means for moving cans or receptacles in time with the liquid moving means so that the cans or receptacles will be at predetermined positions at the

time the paint or fluid is forced from the measuring receptacle.

With the foregoing and other objects in view, the invention consists in the details of 5 construction, and in the arrangement and combination of parts to be hereinafter more fully set forth and claimed.

In describing the invention in detail, reference will be had to the accompanying 10 drawings forming part of this specification, wherein like characters denote corresponding parts in the several views, and in which—

Figure 1 illustrates a view in elevation of 15 an apparatus embodying the invention;

Fig. 2 illustrates a top plan view, the same being partly in section;

Fig. 3 illustrates a sectional view on the line 3—3 of Fig. 2 with part of the can moving mechanism and certain operating parts 20 omitted;

Fig. 4 illustrates a view in elevation partly in section of one side of the machine, and

Fig. 5 illustrates a view in elevation of 25 the discharge nozzles.

In these drawings 10 denotes a frame which is preferably made up of tubular sections and joints, although I do not wish to be restricted with respect to the construction, configuration or proportions of the 30 said frame. A motor 11 is supported on a sill 12 attached to the frame and the said motor drives a power transmitting wheel 13 which is splined on the shaft 14. A friction 35 wheel 15, preferably of some fibrous material is secured on the splined shaft 14 and travels in engagement with a friction disk 16, so that power is transmitted from the motor to the operating parts of the mechanism 40 by these members, the said friction wheel being adjustable on the face of the friction disk, so that it may be moved nearer to the periphery of the said friction disk or toward the axis thereof, according to the 45 revolutions desired. As a means for effecting an adjustment and retention of the shaft, after it is adjusted, the shaft is provided with threads 17 engaged by a nut 18, so that as the nut is turned, the shaft is thrust 50 axially, it being seen that the wheel 13 has a bracket 19 secured to it and embracing the nut 18 so that as the nut is rotated, the shaft is moved axially. Fig. 20 illustrates a lock nut 55 which will hold the shaft at different positions of adjustment.

The friction disk 16 is attached to a shaft 21 and the said shaft has a beveled pinion 22 meshing with a gear wheel 23, whose hub is secured to the sleeve 24 and the said sleeve 60 24 projects from the side of the cam 25 and in the present construction, the cam 25, the cam 26 and the crank arm 27 are shown as made in one piece, so that through the medium of the sleeve and a recessed bearing 65 28, the beveled gear wheel, cams and crank

arm are mounted on a shaft 29, which shaft is supported by the hanging bracket 30, which bracket terminates in a bearing 31 for the shaft 21, and the said bracket is strengthened by a brace 32 secured to the 70 frame. The cam 25 is a grooved cam and the cam 26 is a surface cam and their relation to other parts of the mechanism will be presently explained.

The crank arm has a longitudinally disposed groove 33 which forms a seat and way for the reception of a sliding block 34 and the said block has a wrist pin 35 to which a pitman 36 is connected, the said pitman being attached to a piston rod 37 by the collar 38 which has a wrist pin on which the pitman is pivoted. The sliding block 34 has a threaded aperture 39 in which an adjusting screw 39 is threaded, the said adjusting screw being trunnioned at its lower end 40 in the crank arm or in a plate 41 secured to the said crank arm. Near the upper end of the screw, there is a trunnion 42 which rotates in an aperture of the plate 43 of the crank arm and the said end of the said screw 44 has a wheel 43 fixed to it by which it may be turned for moving the block longitudinally of the crank arm, so that it may be brought nearer to or farther from the center of the crank arm for the purpose of increasing or diminishing the throw of the pitman which operates the piston rod of the pump. After adjustments have been attained, a lock nut 44 may be employed to hold the screw at different positions of adjustment in a manner well known. In order to make it possible to set the sliding block so that the piston rod will be given a predetermined movement, graduations 45 may be arranged on the surface of the crank arm and an indicator such as an arrow 46 may be applied to the surface of the sliding block so that when the indicator is brought into alinement or registry with the graduations or any one of the graduations, the operator will know the amount of fluid which will be delivered when the parts are in such adjustment. In the present embodiment of the invention, it is the purpose of the inventor to have these 110 graduations indicating gallons or fractions of gallons which will be moved at each impulse or operation of the pump, it being understood that the piston rod is one element of the pump and that it is connected to a piston 47 within the cylinder 48, here shown 115 as being supported in horizontal position by the frame.

The cylinder has a head 52 through which the piston rod operates and the opposite end of the cylinder is supplied with an intake 120 nozzle 53 threaded as at 54 to receive a hose or pipe coupling which will lead to the source of supply so that upon a piston being retracted or moved toward the rod under the end of the cylinder, paint or fluid will 125 130

be drawn into the cylinder. The joint or coupling between the nipple and the cylinder is provided with a valve seat 55 adapted to engage a valve 56, the said valve having a 5 stem projecting upwardly and being suitably guided so that it will operate to seat and unseat as the piston is moved. The valve has a valve stem 57 which constitutes a guiding means for the valve and its upper 10 end has a collar 58 on it engaged by an arm 59 and the said arm is oscillatably mounted on a shaft 60 which projects through the head 61 of the cylinder and is journaled therein, the said shaft being operated by 15 the handle 62 on the outside of the cylinder.

A discharge spout 63 communicates with the cylinder at the top through the coupling 65 and said coupling has a valve seat 66 engaged by a valve 67 which will seat and unseat so as to close when the piston is moved inward and open when the piston is moved outward and forcing liquid or paint from the cylinder, so that the said paint may find its 25 way to the discharge pipe 63 and from there to the nozzle head 68. The valve 67 has a stem 69 which is in alignment with the stem 57 and the said stem 69 is engaged by an arm 70 on the shaft 60 so that the arms 59 30 and 70 coact to unseat both the valves 56 and 67 if the handle 62 is manipulated.

The discharge pipe 63 has a plate or shaft 71 extending from it and the nozzle head 68 is rotatably mounted on it, said nozzle head 35 having a plurality of nozzles or branches 72, 73, 74 and 75 of different bores or diameters which may be moved so that they aline or register with the discharge spout for the purpose of filling cans of different sizes and 40 the nozzle head is held at different positions of adjustment by the spring 76 which encircles the shaft 71 and bears against the nut 77 on the said shaft and against the nozzle head to force the nozzle head normally inward, 45 there being a pin and socket connection between the nozzle head and the discharge spout which will hold the head against rotation except when it is pulled outwardly against the action of the spring 76 to cause 50 a dislodgment of the pin from the socket. It is immaterial which member carries the pin and which member has the sockets as the principle of operation will be the same in any event, but in the present embodiment 55 of the invention, the head is shown as having a plurality of sockets 78 and the discharge spout has the pin 79 adapted to enter one of the sockets when the head is moved for the purpose of bringing a certain 60 nozzle into registry with the discharge spout.

As a means for preventing dripping of material which would soil the cans or the table on which the cans are moved, as will 65 presently appear, a drip collecting trough 80

is supplied to coact or move with other parts of the mechanism in proximity to and under the discharge nozzle which is being used and in order to move this trough into operative position when a can is not in place to be 70 filled, the said trough has an extension 81 mounted on a pivot 82 of a bracket 83 and the rear end of said extension is bifurcated to form a recess 84 which receives a flange 85 of a collar 86 and the said flange is moved 75 by a rod 87 to communicate oscillatory motion to the trough. At the rear of the trough, there is a drip hole 88 which permits fluid or paint which has accumulated in the trough to escape and gravitate into a receptacle 89 and the receptacle is held by a bracket 90 carried by the frame.

The rod 87 reciprocates in guides 91 of the frame and it is operated by the cams 26 through the medium of the coupling 92 and 85 the rod 93, which latter carries a cam-engaging roller 94. The manner of transmitting motion from the cam to the trough may be modified, but in the present embodiment, the cam is so thrown or shaped as to move 90 the rod outwardly and oscillate the trough so that it will move under the discharge nozzle at the time the pitman is moving rearwardly to carry the piston in the cylinder in a direction to draw a fresh charge of 95 fluid into the cylinder, and it is then that the dripping fluid might reach the table or the next succeeding can and result in daubing the table or can.

A spring 95 encircles the rod 87 and bears 100 against the collar 96 and one of the guides 91, the said spring being effective to hold the cam wheel in engagement with the cam and move the trough from under the discharge nozzle when the depressed face of the 105 cam permits it. The cam 25 reciprocates the cam rod 97 and a link 98 is pivoted to the cam rod and to a lever 99, which lever is oscillatably mounted on a vertically disposed stud 100. The lever 99 has a link 101 110 at its end by which it is connected to a head 102 oscillatable on guide rods 103.

The link 101 has a sleeve 101^a which is adjustable on the vertically disposed rod 101^b attached to the outer end of the lever 99, so 115 that the sleeve 101^a may slide on the rod to compensate for the movement of the table which is of course vertically adjustable for the purpose of accommodating cans of different heights. The table is shown as having screw threaded supporting rods A which are suitably guided on the frame and they have beveled gear wheels B engaged by gear wheels C on the shaft D which shaft is operated by a crank E for rotating the said 120 shaft in either direction to raise or lower the table, according to the requirements. The crank is held against movement by a pin F which enters an aperture in the disk C when the spring H forces the said pin in the said 125 130

seat and as the table is elevated or lowered, the sliding collar 101^a is free to move longitudinally of the rod 101^b.

The head has a recess 104 in which an arm 105 is seated and held by a set screw 106, the said arm constituting a support and carrier for the block or body 107, it being understood that the block 107 is adjustable on the rod and that it is held at different 10 positions of adjustment on the said rod by the set screw 108. The block 107 has a pawl 109 connected to it by the pivot 110 so that the pawl may oscillate and one end of the pawl is under pull of the spring 111 which 15 is connected to it and to a stud 112 carried by the block 107 and the degree of movement which may be imparted to the pawl is limited by a stop pin 113 into engagement with which the pawl is pulled by the spring. 20 It will be seen from the foregoing description, therefore, that as the lever 99 oscillates, it will communicate motion to the block 102 and through the medium of the rod 105, motion will also be communicated 25 to the block 107 and the parts associated with it.

The table 114 which is designed to support cans to be moved into position under the nozzle or that nozzle which is set to 30 discharge material has, in the present embodiment of the invention, two stud shafts or studs 115 and 116 on which sprocket wheels 117 and 118 are mounted respectively and these sprocket wheels are engaged by a 35 sprocket chain 119, the said sprocket chain being made up of links with interposed arms 120 pivotally connected to certain of the links. The arms are of irregular configuration, that is to say, they are bent to 40 form recesses 121 which form seats for the cans to be engaged and moved as the arms travel. Each arm has a stud 122 which, in turn, is engaged by the end of the pawl 109, the end of the said pawl being provided with a recess 123 to form a seat for 45 the reception of the studs of the arms.

The throw of the lever 99 is such as to move cans under the discharge nozzle successively and provision is made for moving 50 cans of large or small diameter, yet centering them with respect to the discharge nozzle, the said adjustment being accomplished through the medium of the set screw 109 by which the block 107 may move with relation to the lever.

In order that it may be understood how the invention is carried into practice in this regard, it may be stated that when, for example, a lot of large cans have been filled 60 and it is desired to fill a lot of smaller cans, one of the latter will be placed centrally under the discharge nozzle and the set screw 108 will be released and the block 107 shifted until the crotch or recess of the arm 120 65 comes in contact with the can. The set

screw is then tightened and the machine will be operated so that successive cans are brought into proper position with relation to the discharge nozzle, it being observed that the travel of the sprocket chain remains 70 always the same for each operation, while the distances between the arms are uniform so that when the mechanism is adjusted for one can of any size, each similar can thereafter will be accurately centered under the 75 nozzle.

The nozzles are threaded externally for the purpose of effecting the coupling of a hose or pipe which may be used for circulating a cleansing fluid through the pump 80 and valve casings or ports, this being effected by threading a hose on the intake nozzle and having the hose from the discharge nozzle to the intake nozzle inserted in a receptacle containing gasolene or other paint 85 solvent and then operating the pump so as to circulate the cleansing fluid in the same path as the paint has been caused to travel by the operation of the said pump. It has been found in practice that comparatively 90 few impulses of the pump will suffice to cause the cleansing fluid to remove deposits of paint from the surfaces of the cylinder, piston and pipes and make the apparatus ready for operation on paints of other colors and this can be accomplished with the use of comparatively little cleansing fluid 95 since it can be recirculated until traces of paint deposit are removed.

The construction and operation of the apparatus will, it is thought, be understood from the foregoing description of the parts of the apparatus and the functions which have been ascribed to them, but in order to insure an understanding of the operation, 100 it may be stated that when a batch of paint has been prepared for packing, the hose or pipe from the intake nozzle will be inserted in the receptacle containing the paint and the can supporting table and the can conveyer thereon will be adjusted with relation to the discharge nozzle so that a can moving on the table can pass under the discharge nozzle, the adjustment of the table being attained by the elevating and lowering 105 means which have been described, whereas the adjustment of the conveyer for moving cans of a certain diameter will be effected through the adjustment of the can engaging arms, a description of which has 110 been given.

Having in mind then, the capacity of the cans to be filled, the piston operating pitman will be adjusted on the said piston or the sliding block to which the said pitman is 125 connected will be adjusted on the crank arm according to the graduations on the crank arm so that the piston will be given a movement to insure the drawing of an amount of paint within the cylinder which will fill 130

the can to be packed, after which the power may be applied to drive the mechanism. It is desirable to operate the mechanism as rapidly as possible without splashing the fluid and that will depend to some extent upon the thickness of the fluid and in order to provide for different speeds, the friction wheel and friction disk are supplied, the shaft of the said friction wheel having 5 means whereby it can be adjusted to increase or diminish the revolutions of the disk.

As the piston reciprocates and is drawn rearwardly, a given quantity of paint will be drawn into the cylinder through the 10 valve at the intake nipple and the valve at the discharge spout will, of course, be closed. Upon movement of the piston in the opposite direction, the valves will be oppositely influenced and the discharge valve will be 15 opened to permit the paint to enter the discharge spout from which it will pass to the nozzle into the can. When the piston has reached the limit of its outward stroke, fluid or paint which has passed the baffle, will 20 descend by gravity, but there will be no dripping of material from the discharge spout proper, as the baffle will correct any fault of that kind. The cams and the connections are so arranged and timed that on 25 the return movement of the piston, the rod which is connected to operate the drain trough will oscillate the trough so as to force the outer end thereof under the nozzle to catch any drippings which may be discharged while the cans are being shifted for 30 the purpose of removing the filled can and bringing an empty one into position to be filled, and the cam which operates the trough is also so timed that it will cause the trough 35 to move out of alignment with the discharge nozzle when the piston starts to again deliver fluid through the discharge pipe, it being understood also that the cam which operates the lever for actuating the conveyer 40 is likewise timed to move a can while the trough is under the discharge nozzle, and, therefore, the movement of the can into place, its removal after it is filled, the means for forcing the fluid into the can, are automatically accomplished, and the provision 45 for setting the parts of the apparatus to gain the result may be expeditiously accomplished.

I have used the terms paint, fluid or liquid 50 in this specification and while the apparatus is primarily designed for filling cans with paint, it can operate on other fluids and, therefore, the terms are used synonymously and without conflict.

60 I claim—

1. In a can filling machine, a cylinder having inlet and discharge ports, a piston and piston rod operating therein, a rotary member having a crank arm and cams associated with it, means for connecting the 65

piston rod and crank arm, a cam rod operated by each of the said cams, a nozzle through which the cylinder discharges, a trough, means for connecting a cam rod to the trough for oscillating the trough whereby it will move under or away from the nozzle, a can moving mechanism operated by the other cam rod, and means for driving the rotary member. 70

2. In a can filling machine, a cylinder 75 having inlet and discharge ports, a piston and piston rod operating therein, a rotary member having a crank arm and cams associated with it, means for connecting the piston rod and crank arm, a cam rod operated by each of the said cams, a nozzle through which the cylinder discharges, a trough, means for connecting a cam rod to the trough for oscillating the trough whereby it will move under or away from the 80 nozzle, a can conveyer operated by the other cam rod including can engaging arms, a chain to which the arms are connected, a reciprocating block, a lever interposed between the cam rod and said reciprocating block for moving the said block, means carried by the said reciprocating block for communicating motion to the cam arms, and means for driving the rotary member. 85

3. In a can filling machine, a cylinder 90 having intake and discharge ports, valves for controlling the said ports, a discharge spout communicating with the discharge port, a nozzle in communication with the discharge spout, a piston in the cylinder, a 100 piston rod connected thereto and extending beyond the cylinder, a pitman connected to the piston rod, a crank arm, means for adjustably connecting the pitman to the crank arm to increase or diminish the throw of the 105 piston rod, cams operating in conjunction with the crank arm, a drip trough, means for pivotally supporting the drip trough whereby it will move into or out of alignment with the discharge nozzle, a cam rod 110 operated by one of the cams and connected to the trough for oscillating the said trough, a cam rod reciprocated by the other cam, a lever, means for pivotally supporting the lever, means for communicating the motion 115 of the second mentioned cam rod to the said lever, a reciprocating member, means for communicating the motion of the lever to the reciprocating member, a table in conjunction with which the said reciprocating member moves, and a can conveying mechanism associated with said reciprocating member and operated thereby. 120

4. In a can filling machine, a cylinder 125 having inlet and discharge ports, a piston and piston rod operating therein, a rotary member having a crank arm and cams associated with it, means for connecting the piston rod and crank arm, a cam rod operated by each of the said cams, a nozzle 130

through which the cylinder discharges, a trough, means for connecting a cam rod to the trough for oscillating the trough whereby it will move under or away from the nozzle, a moving mechanism operated by the other cam rod, a conveyor comprising a table, a flexible conveyor member, means for guiding the conveyor member, a reciprocating member and means for guiding the said member, arms on the flexible member, a device carried by the reciprocating member adapted to communicate motion to the arms successively, means for moving the reciprocating member and means for applying power to the machine.

5. In a can filling machine, a cylinder having inlet and discharge ports, a piston and piston rod operating therein, a rotary member having a crank arm and cams associated with it, means for connecting the piston rod and crank arm, a cam rod operated by each of the said cams, a nozzle through which the cylinder discharges, a trough, means for connecting a cam rod to the trough for oscillating the trough whereby it will move under or away from the nozzle, a can moving mechanism operated by the other cam rod, a table, shafts extending upwardly therefrom, wheels rotatably mounted on the shaft, a flexible member extending around the said wheels, arms carried by the flexible member, a reciprocating member, means for guiding the reciprocating member with relation to the table and said flexible member, means carried by the reciprocating member for engaging the arms successively for moving said arms, means for moving the reciprocating member, and means for applying power to the machine.

40 6. In a can filling machine, a cylinder having inlet and discharge ports, a piston and piston rod operating therein, a rotary member having a crank arm and cams associated with it, means for connecting the
45 piston rod and crank arm, a cam rod operated by each of the said cams, a nozzle through which the cylinder discharges, a trough, means for connecting a cam rod to the trough for oscillating the trough where-
50 by it will move under or away from the nozzle, can moving mechanism operated by the other cam rod, a table, shafts extending upwardly therefrom, wheels mounted on the shaft, a flexible member engaging said
55 wheels, arms projecting from the flexible member adapted to engage cans, studs on the said arms, a reciprocating member, a pawl pivotally connected to the said reciprocating member, means for holding the nose of
60 the pawl in position to engage studs of the arms, means for moving the reciprocating member, and means for applying power to the machine.

7. In a can filling machine, a cylinder having inlet and discharge ports, a piston

and piston rod operating therein, a rotary member having a crank arm and cams associated with it, means for connecting the piston rod and crank arm, a cam rod operated by each of the said cams, a nozzle through which the cylinder discharges, a trough, means for connecting a cam rod to the trough for oscillating the trough whereby it will move under or away from the nozzle, can moving mechanism operated by the other cam rod, a table, shafts extending upwardly therefrom, wheels mounted on the shaft, a flexible member engaging said wheels, arms projecting from the flexible member adapted to engage cans, studs on the said arms, a reciprocating member, a pawl pivotally connected to the said reciprocating member, means for holding the nose of the pawl in position to engage the studs of the arms, means for moving the reciprocating member, means for adjusting the reciprocating member with relation to the means for moving it, and means for applying power to the machine.

8. In a can filling machine, a cylinder 90 having inlet and discharge ports, a piston and piston rod operating therein, a rotary member having a crank arm and cams associated with it, means for connecting the piston rod and crank arm, a cam rod operated by each of the said cams, a nozzle through which the cylinder discharges, a trough 95 for oscillating the trough whereby it will move under or away from the nozzle, can moving mechanism operated by the other cam rod, a table, shafts rising therefrom, wheels mounted on the shaft, a chain operating over the said wheels, arms carried by the said chain, studs on the said arms, a reciprocating member; means for guiding the reciprocating member with relation to the table and the chain, a block carried by the reciprocating member, a pawl 105 pivotally connected to the block, means for adjusting the block with relation to the reciprocating member, means for holding the pawl in engagement with the studs of the arms, means for moving the reciprocating member, and means for applying power 110 to the machine. 115

9. In a can filling machine, a cylinder having inlet and discharge ports, a piston and piston rod operating therein, a rotary member having a crank arm and cams associated with it, means for connecting the piston rod and crank arm, a cam rod operated by each of the said cams, a nozzle through which the cylinder discharges, a trough, means for connecting a cam rod to the trough for oscillating the trough whereby it will move under or away from the nozzle, can moving mechanism operated by the other cam rod, a table, shafts extending upwardly therefrom, wheels on the shaft, a 120 125 130

sprocket chain engaging the wheels, arms projecting from the said chain, said arms having studs thereon, a reciprocating member, means for guiding the reciprocating member with relation to the table and the sprocket chain, a rod carried by the reciprocating member, a block adjustably connect- ed to the rod, means carried by the block for engaging the studs of the arms successively, means for moving the reciprocating member, and means for applying power to the machine.

MAURICE HOFHEIMER.
